UNITED STATES PATENT OFFICE.

CHARLES H. CAMPBELL, OF CHELSEA, MASSACHUSETTS.

CAN.

1,120,276.

Specification of Letters Patent.

Patented Dec. 8, 1914.

Application filed June 11, 1910. Serial No. 566,305.

To all whom it may concern:

Be it known that I, CHARLES H. CAMPBELL, of Chelsea, in the county of Suffolk and State of Massachusetts, have invented 5 certain new and useful Improvements in Cans, of which the following is a specification.

This invention relates to a can for the shipment of perishable goods, and particularly such delicate and perishable food articles as oysters and other shell fish which have been removed from their shells. For the shipment of such goods it is necessary that the containers in which they are placed 15 be clean and sterile and may be closed tightly enough to prevent leakage of the liquor of the shell fish and inward seepage of impurities.

Accordingly, my object in devising the 20 present invention has been to provide a receptacle having these essential qualities, the possession of which is insured by the means which I have devised of securing the cover thereto. The cans when new are clean and 25 fit for use, but after once being used they are unfitted for the purpose until thoroughly cleaned and sterilized. In order, therefore, to prevent second use of such a container and thereby danger of contaminating the oysters or other food supplies of 30 similar nature packed therein, I have devised a mode of connection between the can and its cover which will insure the destruction of the cover when the can is opened, 35 and thus prevent undetected second use of the can. As the can is thus limited to a single use or shipment, it is called a "single trip" can. Incidentally the effect secured also guards against opening of the can and 40 theft of any part of its contents by those employed in shipping or handling the can.

Another object also accomplished by my invention has been to make the can and cover construction of the greatest possible 45 stiffness to resist the tendency of the fluid contents thereof to force the cover off when subjected to pressure enabling light and inexpensive stock to be used in its manufacture, and further to so fashion the can that 50 its lip will be without sharp or ragged

edges, liable to cut the oysters or equally soft and delicate contents, when they are poured from the can.

In the accompanying drawings, I have illustrated a can by which the foregoing 55 objects of my invention are reduced to practice.

Figure 1 represents a perspective view of the top of the can and its cover applied thereto and sealed in place. Fig. 2 represents a sectional view of the can and the cover on the line 2—2 of Fig. 1. Fig. 3 is a section on an enlarged scale through one of the sealing points of the can. Fig. 4 is a sectional view showing an additional seal 60 for guarding against unlawful opening of the can. Fig. 5 is a detail view showing an attachment to the can for starting removal 65 of the cover.

The can body is represented by *a* and is 70 preferably made of tinned sheet metal, as thin as possible, consistent with the service required. The stock from which the body is made may be formed in any approved manner into the required shape, and secured 75 to the bottom *b*. The cover is represented by *c* and is set in place by being crowded into the open end of the can body. The body and cover together form what is known as a friction top can, the cover reinforcing and stiffening the can body and permitting lighter stock to be used in its construction than would be necessary if the ordinary outside slip cover were used. For 80 additional stiffness the body may be provided with a reversed bead *d* surrounding it near its mouth, or with more than one such bead, although the employment of such beads is optional and not material to the present invention. The cover *c* is what is 85 known as a "plug" cover, being formed with a peripheral flange *e* which makes contact with lip or flange surrounding the mouth of the can body over a considerable area and thus forms a frictional lock which 90 alone exerts considerable force in retaining the cover in the can. The frictional engagement between the can body and cover flange, reinforced by the liquid seal caused by the liquor of the contents, closes the can se- 95 100

curely enough for the purpose of as extended shipments and periods of storage as the nature of the goods permits.

In order to lock the cover so securely in the can as to prevent its unauthorized removal, and in fact to prevent its removal at all without more or less complete destruction, and also to insure against undetected second use of the can, I provide a novel mode of forming integral fastenings in or out of the stock of the can body and cover flange. In forming these fastenings I make use of a tool employing elements corresponding to a punch and a die, but of such relative dimensions as will distort the metal to which they are applied, without cutting it. When the closed can is acted upon in this manner, the material is distorted to form interlocking integral protuberances *f* and *g* on the flange of the cover and the can body respectively. Both protuberances are formed in a single operation and one is formed inside of the other. These may be made so as to project outwardly, as shown in Fig. 3, or in the opposite direction, according to the manner in which the tool is used. In any case, however, one of the two elements composed of the cover flange and can lip has formed upon it an integral offset which is contained in a corresponding offset in the other of these elements. The shape of the tool for making the offsets is such that the offsets or protuberances are formed with sides as nearly as possible perpendicular to the adjacent surface from which they project, and they project as far as permitted by the strength and ductility of the metal, which is farther than the rim of the can or the flange of the cover can be displaced without permanent distortion. That is, to employ a term of applied mechanics, the extent of the protuberances is greater than the possible amount of distortion of the can body and cover flange which can be produced within the limits of elasticity of the material, so that in order to remove the cover either the can body or the cover, or both, must be distorted beyond the elastic limit and permanently bent or broken, or cut. The metal which is distorted to form the protuberance *g* is thus distorted beyond the elastic limit and receives a permanent set. The sheet metal used for such cans is sufficiently ductile to enable the protuberances so formed to project farther than the cover flange or can body can be distorted elastically. The protuberances thus formed constitute integral hollow rivets on one of the elements above described contained in recesses of the other element. These fastenings are intentionally made so abrupt that they can not be withdrawn from the coöperating sockets without either

being broken or sheared off themselves, or without causing such distortion or shearing of the can cover as will prevent its second use. In particular the formation of the fastening elements in the can body is such as to make it impossible to apply a new cover and secure it in this manner without making the substitution plainly evident. In order to increase this effect, some of the fastenings are directed outwardly and others inwardly, and in regard to the inwardly directed fastenings, it is obviously impossible for a coöperating protuberance on a new cover to register therewith in such manner as to avoid detection.

In connection with the integral fastenings I propose to use a seal in the nature of a wire *h* passed through registering holes in the can body and cover, the end of such wire being caught in a disk *i*, the nature of which is similar to that of the ordinary lead and wire seal. As shown in the drawings, the edge of the can body is turned over to form an outward bead *j* presenting a smooth surface to the contents of the can when they are poured out, and thus eliminating sharp edges which would be liable to cut such soft articles as oysters.

Another feature of value and importance to the can is an attachment which I provide for assisting in starting the cover when the same is to be stripped off. The cover as above described is so securely held that in order to permit of its being pried off when the can is finally to be opened, I provide one or more brackets *k* which are attached to the lip of the can on the outside, and each of which supplies a fulcrum for an instrument such as a screwdriver inserted under the lip of the cover flange. There may be one, two or any number of such brackets attached to the can, preferably as shown in Fig. 5, being shaped to fit around the bead *j* of the can and soldered thereto, and having a brace portion soldered to the side of the can.

I claim,—

1. A single trip can comprising a body having an open end, a friction top set into such open end and having a flange fitting closely within the lip of the can body, said flange and lip having interengaging integral rivet like projections, approximately perpendicular to the longitudinal elements of the can, the sides of which are abrupt, and the lengths greater than the amount by which the flange or lip can spring at the points where such projections are formed, whereby to prevent removal of the cover in an intact condition.

2. A can having an opening and a lip surrounding said opening, and a cover having a flange concentric with said lip and making a close fit therewith, the flange and

lip forming frictional engaging elements, the material of one of such elements being locally distorted abruptly and the other element having an alined recess containing such distorted portion, into which the latter projects a distance greater than the amount either element is able to spring.

In testimony whereof I have affixed my signature, in presence of two witnesses.

CHARLES H. CAMPBELL.
